(57) **CLAIM**

The ornamental design for a carrying pouch, as shown and described.

DESCRIPTION

FIG. 1 is a front view of a carrying pouch in a closed condition.

FIG. 2 is a back view of the carrying pouch of FIG. 1 in the closed condition.

FIG. 3 is a side view of the carrying pouch of FIG. 1 in the closed condition.

FIG. 4 is a side view of the carrying pouch of FIG. 1 in the closed condition.

FIG. 5 is a front view of the carrying pouch of FIG. 1 in an open condition; and,

FIG. 6 is a back view of the carrying pouch of FIG. 1 in the open condition.

The long dashed lines in FIGS. 1 and 5 represent stitching that forms part of the claimed design. The short dashed lines in FIGS. 2 and 6 represent aspects of the design that form no part of the claim.

1 Claim, 4 Drawing Sheets

FIG. 2

FIG. 1

FIG. 3

FIG. 4

FIG. 5

FIG. 6
